UNITED STATES PATENT OFFICE.

WILLIAM B. TURNER, OF NEW YORK, N. Y., ASSIGNOR TO THE TURNER-BEARD AUTOMATIC BRAKE COMPANY.

AUTOMATIC CAR-BRAKE.

SPECIFICATION forming part of Letters Patent No. 367,077, dated July 26, 1887.

Application filed December 6, 1886. Serial No. 229,777. (No model.)

To all whom it may concern:

Be it known that I, WILLIAM B. TURNER, a citizen of the United States, and a resident of the city, county, and State of New York, have 5 invented a new and useful Improvement in Car-Brakes, of which the following is a specification.

This invention is designed as an improvement on the car-brake covered by Letters Patent of the United States Nos. 268,754, 268,755, 10 278,833, 278,834, 278,835, and 336,026, and relates to that class of brakes in which the brake mechanism is put in operative position by the inward movement of the draw-bar, the brake 15 operating always by the movement of the forward draw-bar and never by the rear draw-bar, and in which the power to apply the brake is derived from a friction-collar secured upon one of the car-axles and arranged to operate, through the medium of a friction-wheel, 20 certain novel mechanisms especially designed for the purpose of utilizing the rotary movement of the axle and the momentum of the car for applying the brake.

Embraced in the invention are new devices 25 for transmitting the motions of the draw-bar to the brake mechanism; novel devices, including a reversible clutch, by means of which the brake is rendered operative in whichever 30 direction the car may be pulled, and by which the brake may be rendered inoperative when desired, and other improved devices which, in co-operation with those alluded to, assure the accuracy and efficiency of the brake, all 35 of which will be hereinafter fully set forth.

Reference is to be had to the accompanying drawings, forming part of the specification, in which similar letters of reference indicate corresponding parts in all the figures.

Figure 1 is a partly-sectional side elevation 40 of a car body and truck, showing my improved brake in place, with parts broken away to exhibit other parts. Fig. 2 is a plan view of a portion of a car body and truck, with parts 45 broken away, showing certain portions of my improved device in position. Fig. 3 gives several views of my improved reversible clutch and details thereof, the latch portion enlarged. Fig. 4 shows in two positions a portion of the 50 mechanism for transmitting the motion of the draw-bar to the friction-wheel and a part of

the device for changing the direction in which the brake will operate and for rendering the brake inoperative. Fig. 5 is a front elevation showing in several positions—indicated, respectively, by full and dotted lines—a portion of the transmitting and direction-changing mechanism, and also the connected slotted lever through the medium of which the reversible clutch is operated. Fig. 6 shows three 60 views of parts of the transmitting and direction changing mechanism. Fig. 7 is a side elevation of the disengaging lever. Fig. 8 is a plan, with parts broken away to exhibit other parts, showing the reverse side of the push-bar, push-bar guide-plate, and the double-acting multiplying-lever in position. Fig. 9 is an edge elevation of the push-bar guide-plate and multiplying-lever. Fig. 10 is a side elevation of a hanger and attached bell crank. Fig. 11 65 is a plan of the above hanger. Fig. 12 is a side elevation of the lever for operating the clutch. Fig. 13 is a sectional elevation of the device regulating the pressure of the friction-wheel against the axle-collar.

In the drawings, A represents a car-body; B, the car-axles; C, the car-wheels, and C' a collar rigidly secured on one of the axles.

D represents an ordinary draw-bar; D' and D², respectively, the usual follower-plates, and 80 D³ the usual spring about the draw-bar shank.

D⁴ indicates the usual brake-levers, D⁵ the brake-beams, and D⁶ the brake-shoes.

The front follower-plate, D', is adapted to be moved rearward by the compression or 85 pushing in of the draw-bar and forward in normal position, as shown in Fig. 1, by the reaction of the spring D³. Secured to the front follower-plate by a hooked bolt, a, so as to transmit the motion of said plate, is a push-bar, E, whose free end terminates in or with a rectangular block, a', moving in a guide-plate, a², Figs. 1, 2, 8, and 9, which is fastened to the under side of the car-timbers A'.

The double-acting multiplying-lever F (best 95 shown in Figs. 2, 8, and 9) is, in order to receive motion from the push-bar E, pivoted on the plate a² in such a manner that the bottom of its foot is in contact with one side of the block a', the beveled toe b of the said lever extending over and past a corner of said block 100 and the lever-heel b' resting against the oppo-

site block corner, the bottom of the lever-foot and the toe and heel forming, as it were, a pocket embracing said block and making contact connection therewith on three sides there- 5 of, gripping or clutching it between toe and heel; and the head of said lever, extending laterally, is bored transversely, as indicated, and has secured in it by nuts b^2 the forward end of a rod, F' , whose broadened rear end is 10 to shouldered on its lower edge, as shown at b' , for purposes hereinafter explained.

When the parts are in normal position, with the car moving in the direction of the arrow, Fig. 1, the rear end of the rod F' is entered between the sides of the slotted lever G and hooks over the lower bar thereof, as shown in Figs. 1 and 4. This lever G has a forward hooked extension, b^4 , and is centrally pivoted on a frame-piece, G' , which is rigidly secured 20 on the car-body, as shown, and pivoted on the same pivot, b^5 , and on the same support or frame-piece, Fig. 4, and in side contact with said lever G , is a disengaging-lever, G^2 , whose extremities are bent at right angles to 25 its body, as shown in Figs. 4 and 7, and said lever G^2 is provided with a stud, b^6 , extending from a side thereof to enter the slot of the triangular lever G^3 . On a pillar, c^1 , projecting from the same support or frame-piece, G' , and 30 in side contact with the disengaging-lever G^2 , is pivoted the triangular lever G^3 , having a nearly central curved slot, c , for the reception of the stud b^6 of the lever G^2 , and a fork, c' , for the reception of an end of a pointed lever, 35 G^4 , and a swiveled eyebolt, c^2 , free to turn in its socket, whose functions will be hereinafter set forth.

On an extension of the frame-piece G' is pivoted the pointed lever G^4 , Figs. 1, 4, and 40 5, the smaller end of which is engaged in the fork c' of the lever G^3 , while its other end is connected by a rod, c^3 , Figs. 1 and 5, with the free end of a cam-lever, H , (provided with a slot, d ,) that is pivoted at its other end on a 45 hanger, H' , which is secured to the car-truck, as shown in Figs. 1 and 5. This hanger H' has a forked lower end, as shown in Fig. 11, in which is pivoted, as shown in Fig. 10, a bell-crank, I , in the elbow of which is journaled one end of the shaft K , carrying the friction-wheel K' , while the other end of said shaft is journaled in a hanger, H^2 , Fig. 2, also secured on the car-truck.

As the bell-crank elbow is capable of movement in an arc of a circle, and as the friction-wheel K' is fixed on that end of the shaft K nearest said bell-crank and directly opposite the axle-collar C' , it will be seen that the said friction-wheel may be readily moved to make 55 60 peripheral contact with the axle-collar, so that it may partake of the rotary motion of the same. The said bell-crank is connected by a rod, d , to the hook of the slotted lever G , as shown in Fig. 1, and receives motion there- 65 from.

On the shaft K is a clutch composed of a cylindrical shell, f , loosely set thereon, and hav-

ing opposite longitudinal grooves f^1 formed in its inner face, in which are placed latches f^2 , pointing in opposite directions, about whose lateral studs f^3 are secured springs f^4 . The clutch consists, further, of a longitudinally-grooved block, f^5 , rigidly secured on the shaft K and fitting within the shell f , which latter is made to revolve with the said block when 75 one of the shell-latches engages in one of the block-grooves; and it consists, further, of a clutch-fork, f^6 , designed to slide on the shaft K and have its legs move in the block-grooves f^1 , in order to make the clutch operative or inoperative, as the case may be, all of which is best shown in Fig. 3. The legs of the fork f^6 are of equal length, but not of equal size. The extremity of one is pointed or beveled, the rest of its shank being of full size throughout, 85 while the extremity of the other has on it a boss, f^7 , projecting laterally outward. The operation of this clutch is as follows: When the fork f^6 is pushed its full length into the cylindrical portion of the clutch, into the 90 grooves of the block f^5 , the full size of the shank of the pointed leg is presented to one of the latches f^2 , thereby holding the latter in its shell socket or groove and preventing it from engaging in a groove, f^1 , of the block. 95 The other latch will, as the block is turned in the shell f , come behind the boss f^7 of the other fork-leg, the said boss being pushed beyond the said latch, (as indicated in dotted lines, longitudinal elevation, Fig. 3,) and then, 100 owing to the depression in the said leg back of said boss, said latch will be forced by its spring to engage against one side of the block-groove which is directly opposite it. When this latch is engaged in the block-groove, as 105 set forth, the block, being turned in the proper direction, will carry the shell with it, the said latch operating as a pawl, extending from shell to block and connecting the two. This shell f has an outwardly-projecting lug, g , to which 110 is secured a brake-chain, g' , which, passing over a sheave, g^2 , is made fast at its other end to a brake-lever, D' , as shown in Figs. 1 and 2.

When the fork f^6 is pulled out to its central position, (as shown in full lines, longitudinal 115 sectional elevation, Fig. 3,) the boss f^7 makes contact with (is drawn under) the shell-latch which is engaged in the block-groove, as aforesaid, and lifts it out of said groove. At the same time the pointed leg is equally drawn out, 120 but not sufficiently to release the other latch and permit its engagement in its block-groove, so that now both latches are disengaged from their respective block-grooves, and the block can revolve within the shell without turning 125 the latter. This is what is called the "central position" of the clutch—i. e., when the shaft K , with the block f^5 , may revolve in either direction without revolving the shell f with them, and consequently without operating to 130 effect the brake.

When the fork f^6 is drawn out to its full extent, (to the position shown in dotted lines, longitudinal sectional elevation, Fig. 3,) the shank

of the pointed leg is drawn from beneath its latch, thereby permitting the latter to become engaged, by the action of its spring, in the corresponding block-groove, that it may operate to cause the shell f to revolve with the block when the shaft K revolves, but in the direction opposite to that in which it would be revolved if the other latch were engaged. At the same time the boss f^s on the other leg is not drawn out far enough to permit this other latch to engage with the block, but still holds said latch out of its block-groove. Hence it will be seen that this clutch can only be made operative for one direction at one and the same time, that it can be rendered entirely inoperative, and that its action can be changed to suit the direction desired.

A clutch-yoke, M , Figs. 1, 2, and 12, pivoted on a lateral extension of the hanger H' , as best shown in Fig. 2, has its tail engaged in the slot of the cam-lever H and its forks embracing the grooved neck of the clutch-fork f^s , so that when the said lever H is moved up and down, the said yoke M is correspondingly made to force the clutch-fork f^s in or out, as the case may be, of the clutch-block-grooves and hold it in the position assumed.

On the forward end of the car frame is secured a timber, N , extending upward, and having fixed on its top, Figs. 1 and 2, a segmental plate, O , provided with edge notches or sockets h . Directly beneath this plate O a lug or step, O' , is secured on the under side of the car-timber, and a rod, O^2 , extending from plate O to step O' , is pivoted in them. On the upper end of this rod O^2 is secured a hand-lever, O^3 , with which to turn the said rod, and pivoted on said lever is a gravity-pawl, O^4 , which is designed to engage in any one of the notches h , and thereby hold the rod O^2 in desired position. On the lower end of the rod O^2 is rigidly secured, parallel with the lever O^3 and pointing in the opposite direction thereto, an arm or crank, O^5 , which is connected by an adjustable rod, P , made adjustable in length between its end connections by nuts k , with the swiveled eyebolt c^2 of the triangular lever G^3 , which eyebolt is free to turn in accordance with any change in the angular direction of the rod P , and thereby prevent undue strain upon or distortion of the parts.

The action of this brake is as follows: When the parts are in the positions shown in Fig. 1 and the car is being pulled in the direction of the arrow, the brake is in position to operate in that direction of motion. Then, if the engineer desires to set the brake, he slows the engine, and the momentum of car, forcing the car forward, brings the head of the draw-bar D against the draw-bar of the engine or car in front of it, with the effect of pushing said draw-bar D rearward, carrying with it the follower-plate D' , the motion of which latter is transmitted to the push-bar E , with the effect of turning the double-acting multiplying-lever F on its pivot and causing it to pull the rod F'

forward. The push-bar E , in its rearward movement, is forced against the toe b of the lever F , and said toe is so shaped and located that it is moved and held by the terminal block a' of the push-bar E out of the direct line of motion of said bar when the lever F has been turned sufficiently to produce desired action, and any further rearward thrust of said push-bar produces no effect nor can do any injury to the parts of the brake mechanism, howsoever great or violent may be its movement. About half an inch inward movement of the draw-bar D suffices to operate the brake. The rod F' , being engaged with the lower bar of the slotted lever G , is made by this movement of the lever F to pull the lower end of said lever G forward, causing it to turn on its pivot, and thereby lift through its connections the cylinder Q , spring Q' , and rods $Q^2 R$, hereinafter specified, the free end of the bell-crank I making the elbow of the latter to move rearward with its supported end of the shaft K , so as to force the friction-wheel K' on said shaft in contact with the axle-collar C' , and then the revolution of the car-axle and collar causes the said friction-wheel and its shaft to revolve. On this shaft K is the reversible clutch, the shell f of which has made fast to it one end of a brake-chain, g , whose other end is secured to a brake-lever, D^4 ; hence continued revolution of the car-axle collar in contact with the friction-wheel causes the clutch to revolve, with the effect of winding up the brake-chain on the friction-wheel shaft and thereby applying the brake.

Recurring to the connections above referred to between the slotted lever G and the bell-crank I , it will be seen that below the free end of the bell-crank is a cylinder, Q , containing a spiral spring, Q' , up through which is passed a rod, Q^2 , with a nut, p , on its lower end. This rod Q^2 is passed up through the forward end of the bell-crank I , and has an eye on its upper end, whereby it is connected, by means of the rod R , with the hook b^4 of the slotted lever G . The nut p may be turned up or down on the rod Q^2 in order to adjust the tension of the spring Q' , so that the force with which the friction-wheel is pushed and held in contact with the axle-collar by the upward pull on the spring Q' may be regulated or determined by proper adjustment of said nut p . The brake being applied as aforesaid, should the engineer now desire to release it, he does so by quickening the speed of his engine, and thereby the draw-bar D is pulled out, and with it the follower-plate D' and push-bar E . Now, as the push-bar E is thus pulled out to its normal position, the rectangular block a' comes in contact with the heel b' of the lever F , thereby turning said lever on its pivot back to its normal position, pushing rod F' rearward, thereby releasing the latter from operative contact with the lower bar of the slotted lever G , and allowing said lever and the bell-crank and its connections to also resume their normal positions, thereby bringing the fric-

tion-wheel out of contact with the axle-collar and allowing the brake-chain to unwind and release the brake.

Should the engineer, having the engine attached to the draw-bar D, desire to back the car or train, the parts being in the positions shown in Fig. 1, the pushing in of the draw-bar would, through its connections above described, bring the friction-wheel in contact 10 with the axle-collar, causing the said friction-wheel to revolve; but in this position, as will be observed, because the backing of the car changes the direction of the wheel rotation, and because the clutch is arranged or set for 15 braking when the car is moving forward, the clutch-shell latch heretofore engaged cannot now engage in its clutch-block groove; hence the friction-wheel and its shaft and the clutch-block will revolve without operating the clutch, 20 and without winding up the brake chain, and the car can be freely backed.

Should it be desired to render the brake entirely inoperative, the lever O' must be set so that the pawl O' will engage in the central 25 notch of the segment-plate O with the effect of turning and holding the arm O' at right angles to its former position, (shown in dotted lines, Fig. 1,) thereby operating through the rod P to pull the top of the triangular lever 30 G³ forward, causing it to assume the position shown on the left in Fig. 4, with its forked end but partly depressed. This movement operates on the lever G⁴, engaged in the fork c' of the lever G³, lifting its further end to a 35 horizontal position, so that through its rod c', connecting with the cam-lever H, it raises the latter to the horizontal position shown in the lower dotted lines, Fig. 5. Now, as the tail of the clutch-yoke M is inserted in 40 the slot d of the said cam-lever H, it follows that the said yoke M is so moved by the movement of the lever H as to draw the fork f' out of the clutch so far that the fork-boss f" is brought under its special shell-latch 45 and lifts and holds the latter out of the corresponding block-groove, while the pointed clutch-fork leg still holds its special shell-latch out of its special block-groove, as shown in full lines in longitudinal sectional elevation, 50 Fig. 3. Such being the positions of the parts of the clutch, it is evident that the clutch-shell can freely revolve in either direction, and that, hence, the brake cannot be applied. This inoperative position of the clutch and brake is 55 very desirable when pulling and pushing the cars about the yard. At the same time the triangular lever G³, having the stud of the disengaging-lever G² engaged in its slot, causes by its motion (its top being pulled by the rod 60 P, as aforesaid) said lever G² to move so as to bring its lower offset, s, against the under curved edge of the rod F', thereby lifting the shoulder of said rod out of engagement with the lower bar of the slotted lever G, as indicated on the left in Fig. 4, thus breaking connection between the draw-bar connections and the brake mechanisms, so that the pushing in

of the draw-bar D cannot operate to bring the friction-wheel in contact with the axle-collar. Hence it will be seen that the car may be 70 pushed or pulled in either direction and from either end thereof without applying the brake.

As cars are liable to be handled with either end forward, and as it is desirable to have a 75 brake operative in either direction of the car motion, I propose to attach to the other draw-head (not shown) a push-bar, double-acting multiplying-lever, and a rod F' similar to those shown connected with the draw-bar D and arranged to operate in the same manner, 80 (this second and upper rod F' being partly shown in the right of Figs. 1 and 4.) The said second and upper rod F', however, engages between the upper horns of the slotted lever G, as shown in Figs. 1 and 4, normally 85 resting on the top of the disengaging-lever G², as shown in Fig. 1, and out of engagement with the top bar of the slotted lever G. Now, to make the brake operative when the car is being pulled in the direction opposite to that of 90 the arrow, Fig. 1, the lever O' is to be turned by hand to the position shown in dotted lines, Fig. 1, pointing in the same direction as that in which the car is to be pulled. This change of the position of the lever O' brings the arm 95 O' to the position shown in dotted lines, Fig. 1, and the other parts as shown on the right in Fig. 4 and in the upper dotted lines, Fig. 5, with the outer or free ends of the lever G⁴ and of the cam-lever H elevated to their extreme limits. 100 This permits the shoulder of the second and upper rod F' to fall and engage over and with the upper bar of the slotted lever G, so that said second rod F' may transmit its motion received from its draw-bar connections by 105 pulling on the top of the lever G, thereby producing the same effects as those produced by the first rod F' in pulling in the contrary direction on the bottom of said lever. The clutch-yoke M is by this upward motion of the 110 cam-lever H, last above referred to, brought to such a position as to draw the clutch-fork f" out to its extreme outward position, as shown in the lower dotted lines in the sectional longitudinal elevation, Fig. 3, in which 115 position of said fork the clutch is made operative, after the manner already set forth, for this direction of movement of the car.

It will be seen that when it is designed to make the brake operative the lever O³ is always moved by hand to point in the direction in which the car is to be moving, and when the brake is to be rendered inoperative the said lever O' is to be secured at right angles to the direction of motion, the gravity-pawl o' 120 to be engaged in the central notch of the plate O, so that at a glance the engineer can be assured whether or not the brake mechanism is properly adjusted.

It will be seen that the brake operates always through connection with the forward draw-head, never from the rear draw-head, and when one rod F' is engaged with the slotted lever G the other is always disengaged

therefrom, and both rods F' are disengaged when the brake is rendered inoperative.

I am aware of the United States patents on car-brakes, Nos. 200,602 and 274,388, and do not claim anything therein shown.

Having thus described my invention, I claim as new and desire to secure by Letters Patent—

1. In a buffer car-brake, the combination, with the car draw-bar and front follower-plate and push-bar connected with said follower-plate, so as to partake of the forward and backward motion thereof, of a double-acting lever pivoted with its recessed free end embracing three sides of the free end of said push-bar and at right angles thereto, substantially as herein shown and described, and constructed and arranged to transmit the motions of the draw-bar to the brake mechanism for the purpose of applying or releasing the brake, as set forth.

2. In a buffer-brake, as a means for transmitting the inward and outward motions of the draw-bar transmitted through draw-bar connections to the other parts of the brake mechanism for the purpose of applying or releasing the brake, a double-acting lever, substantially as herein shown and described, fixed at right angles intermediately between the draw-bar connections and the brake mechanism, and having gripping or clutching connection only with the former, as set forth.

3. In a buffer-brake, the combination, with draw-bar D, follower-plate D', connection a, and push-bar E, provided with terminal rectangular block a', of the double-acting lever F, provided with beveled toe b and heel b', arranged at right angles to said bar E, and embracing a side of the terminal block a' between the said heel and toe, substantially as herein shown and described.

4. In a buffer-brake, as a means for transmitting the motions of the lever, which, through its line of connections with the draw-bar, first responds to the movements thereof, to the rest of the brake-levers and other mechanisms for the purpose of applying or disengaging the brake, a shouldered rod, F', substantially as herein shown and described, said rod being connected at one end directly with said lever, and having its shouldered end free to move and adapted to make operative connection with the other mechanism only with its shoulder, as set forth.

5. In a buffer-brake, the combination, with a suitable support, of a slotted lever, G, provided with upper and lower bars and hooked extension b', disengaging-lever G², provided with right-angled offsets s s' and stud b⁶, and triangular lever G³, provided with curved slot c² and swiveled eyebolt c², substantially as herein shown and described, all of said levers being pivoted on the same support and operated as set forth.

6. In a buffer-brake, the combination, with the hooked, barred, and slotted lever G, adapted and arranged to be pulled and thereby have its hook elevated by the transmitted

rearward movement of the draw-bar, and with the shaft K and friction-wheel K', of rod R, cylinder, spring, rod, and nut Q, Q', Q², and p, respectively, and pivoted bell-crank I, all arranged and operating substantially as herein shown and described, whereby said friction-wheel may be forced in contact with the axle-collar, as set forth.

7. In a buffer-brake, the combination, with mechanism adapted and arranged to transmit rearward motion from the draw-bar, and with mechanism adapted and arranged to receive such motion and apply it to the brake-levers, of an intermediate disengaging-lever, substantially as herein shown and described, operative by hand, through suitable mechanism, to break the connection between the said motion-transmitting and the said motion-applying mechanisms, and to hold said motion-applying mechanism in an inoperative condition, as set forth, in order that the car may be pulled or pushed without applying the brake.

8. In a buffer-brake, the combination, with the draw-bar, its spring and follower-plates, car-axle, axle-collar, and brake-chains, levers, beams, and shoes of the usual construction, of a push-bar connected with the front follower-plate and receiving motion therefrom, a lever fixed at right angles to the push-bar and operated thereby, a shouldered rod directly connected with said lever at right angles thereto, a slotted, barred, hooked lever arranged to receive the pull of the shouldered rod, a cylinder containing a spiral spring, up through which is passed a rod with a nut on its end for adjusting the tension of said spring, a rod connecting the slotted lever with the rod within the cylinder and spring, a bell-crank having the extremity of one arm pivoted to a support secured on the car-truck, and the extremity of the other arm held by the said cylinder-rod above the cylinder and carrying in its elbow an end of a friction-wheel shaft, and a shaft with a friction-wheel secured thereon, all constructed and arranged to operate substantially as herein shown and described.

9. In a buffer-brake in which a portion of the mechanism for applying the brake consists of an axle collar and friction-wheel and shaft, the combination, with said shaft, of a reversible clutch, constructed substantially as herein shown and described, consisting of shell f, having internal grooves, externally-grooved block f², spring-actuated latches f², held in the shell-grooves and pointing in opposite directions and adapted to engage in the block-grooves, and clutch-fork f⁶, adapted to be moved to cause the disengagement or to permit the engagement of said latches in the block-grooves, all arranged substantially as set forth.

10. The combination, with a reversible clutch, constructed substantially as herein shown and described, of a pivoted clutch-yoke embracing the neck of the clutch-fork, a lever provided with curved slot for the engagement of the tail of the clutch-yoke, and a rod connecting the unpivoted end of said lever with mechanism

for imparting a vertical motion to said lever, as set forth.

11. In a buffer-brake, the combination, with 15 notched segmental supporting-plate O and supporting-plate O¹, of rod O², hand-lever O³, gravity-pawl O⁴, arm O⁵, and rod P, provided with nuts k k, substantially as herein shown and described, all connected together and arranged and adapted to be operated by hand to make 20 the brake mechanism operative in either direction of the car motion, or to render it inoperative, as the case may be, as set forth.

12. In a buffer-brake, the combination, with 15 mechanism, substantially as herein shown and described, adapted and arranged to be operated by hand to make the brake mechanism operative in either direction of the car motion, or to render it inoperative, as the case may be, and with the brake mechanism, substantially 20 as herein shown and described, of a swivel, c², connecting the two groups of mechanisms, as set forth, whereby any change in the angular

direction of said hand-operated mechanism is taken up or compensated for.

13. In a buffer-brake, as a means for making 25 the brake mechanism, substantially as herein shown and described, operative for applying the brake when the car is pulled with either end forward, the combination, with each draw-bar and its forward follower-plate, of an attached push-bar, double-acting lever, and shouldered rod, all adapted and arranged in combination for transmitting the rearward motion of the draw-bars to the brake mechanism, as set forth.

35 In testimony that I claim the foregoing as my invention I have signed my name, in presence of two witnesses, this 15th day of November, 1886.

WILLIAM B. TURNER.
